[57] CLAIM

The ornamental design for a high pressure soxhlet extractor, as shown and described.

DESCRIPTION

FIG. 1 is a front elevation of a high pressure soxhlet extractor, showing our new design;

FIG. 2 is a right side elevation thereof;

FIG. 3 is a rear elevation thereof;

FIG. 4 is a left side elevation thereof;

FIG. 5 is a top plan view thereof;

FIG. 6 is a bottom plan view thereof;

FIG. 7 is an enlarged cross-section taken on line 7—7 of FIG. 5.

The broken lines representing the porous sample-holding thimble is shown for illustrative purposes only.
